UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

AUTOMOBILE RADIATOR CAP.

Application filed February 21, 1925. Serial No. 10,721.

This invention relates to fittings for the filling spout or nipple of automobile radiators. It is concerned with the provision of a device which is adapted to function effectively as a closure for the spout, as an attractive ornamental feature, and as a means for retaining a temperature indicator or other instrument or decorative device against unauthorized removal or theft.

10 One of the objects of the invention is the provision of a device having these characteristics which may be sold as an accessory for attachment to radiator spouts of the various sizes and kinds used in different makes of 15 automobiles.

A further object is the provision of a construction which is light and may be manufactured quite economically, as from pressed metal.

20 Other and further objects of the invention will be pointed out hereinafter, indicated in the appended claims, or obvious to one skilled in the art upon an understanding of the present disclosure.

25 For the purpose of this application I have illustrated in the drawing forming a part of this specification one embodiment of the invention but it is to be understood that same is susceptible of variation or modification in various particulars without departing from the scope of the invention, which is indicated in the appended claims.

In said drawings:

Fig. 1 is a front elevational view of the 35 device,

Fig. 2 is a sectional elevation taken on line 2—2 of Fig. 3,

Fig. 3 is a sectional view taken on the line 3—3 of Fig. 2 but showing the lateral 40 ornaments in plan view,

Fig. 4 is a sectional detail on line 4—4 of Fig. 3; and

Fig. 5 is a detail illustrating a fastening means.

45 The nature of the invention will be most quickly ascertained by consideration immediately of the illustrative embodiment. Referring to the drawing, let it be understood that the reference character T designates the 50 radiator nipple or spout. Adapted for connection to such spout is a collar member 11 which may be formed as a die casting with an insert 11^a carrying the thread whereby the member is seated on the spout. The 55 collar member has a rear lug 12 and side

lugs 14, and its upper margin forms a seat for cooperation with a sealing closure. This closure includes a cap member 15 which has permanent hinged connection with the lug 12, and is of such size as to cover and encompass the upper portion of the collar member 11 when the closure is in closed position. Preferably it is formed as a sheet metal stamping with a flat top portion 15^a terminating at an annular upstruck bead 15^b 60 so as to form an axial seat for an attachment such as illustrated by the temperature indicating device M, the stem or post of which passes through an axial aperture in the top portion 15^a. The cap member also has a depending skirt portion 15^c above which is a shoulder portion 15^d. Positioned within the cap member is an annular thimble member, preferably formed as a stamping from sheet metal. This thimble member has a peripheral flange portion 16^a which is adapted to 65 fit closely against the inner wall of the skirt portion 15^c, and terminates in an inwardly turned rim 16^b, as best shown in Fig. 5. From the upper limit of the peripheral 70 flange 16^a, the thimble member takes an inwardly extending flat form to provide a gasket seat 16^c, and from the inner margin of this flat portion it extends upwardly as a cylindrical tubular portion 16^d. The upper 75 margin of the latter is received in the inside depression of the bead 15^b and the outer portion of the gasket seat 16^c finds support against the shoulder portion 15^d of the cap member. This places the rim of the skirt portion slightly above the lower limit of the 80 cap portion, which latter is spun inwardly to form the retaining ledge 15^e, as best shown in Fig. 5. A spring wire catch member 17 is positioned in the slot between the margin 85 of the thimble member and the retaining ledge 15^e of the cap, and has portions protruding beyond the inner margins of those members, as illustrated at 17^a in Fig. 3. In the location of these protruding portions, the collar member is provided with grooves or notches forming detent seats with which the spring cooperates to hold the closure in 90 closed position upon the collar.

The instrument or ornament M is secured 105 to the closure in any appropriate manner, preferably in such fashion as to prevent its being readily removed. Such an arrangement is illustrated in Fig. 2, wherein the nut 18 is used to clamp the device securely in 110

place on its seat 15^a, while the member 19 is a tapered spring washer which is wedged into the tubular portion 16^d by means of the follower nut 20, the peripheral engagement 5 of the washer with the tubular portion 16^d being such that the washer can be removed only with a great deal of difficulty, and therefore prevents the securing nut 18 being reached and the device M detached. Sealing 10 gasket 21 is supported against the gasket seat 16^c and is held in place by a washer 22 and nut 24. This gasket 21 is of elastic material and arranged for covering engagement with the upper margin of the collar 11 15 so that when secured in that position it will form an effective sealing closure for the radiator spout.

The device is fastened to the radiator spout in such fashion as to prevent its unauthorized removal, by any suitable means, 20 the form illustrated comprising a headless set screw 25 which is seated in the collar member and arranged for binding engagement with the radiator spout. This headless set screw is tapped axially for reception of the headed screw 26, which latter may be engaged by a screw driver to set up the screw 25 into effective engagement with the radiator spout. Any attempt to back the 25 retaining screw off will simply result in the screw 26 turning in the headless screw 25 without loosening of the latter.

The lateral lugs 14 carry the movable display members 27, which have hinged connection with said lugs by means of the pinnacles 28.

The closure is opened simply by swinging it rearwardly on its hinge with sufficient pressure to cam the detent members 17^a out 10 of the detent seats, and the closing is as easily accomplished by a reversal of that operation. In the manufacture, the necessity for machining or finishing operations is eliminated by forming the parts as above 15 described, while at the same time it is possible, by building the device in this fashion, to utilize materials, such as sheet brass, which will retain a surface finish such as 20 nickel plate effectively and take a good polish.

I claim:

1. An automobile radiator cap comprising a connecting collar, a cap of sheet metal hinged thereto, a thimble member assembled

in the cap member to form a gasket seat, 55 and a detent member retained by the cap and thimble member for cooperation with the collar to hold the gasket compressed between the same and the gasket seat.

2. An automobile radiator closure comprising a connecting collar, a sheet metal cap hinged thereto, a thimble member assembled within the cap and affording a gasket seat and a housing portion, a display device mounted on the cap with its securing 60 means protected in the housing portion, a 65 gasket, and a detent means on the cap for cooperation with the collar to retain the gasket in sealing relationship thereto.

3. A closure for automobile radiator 70 spouts comprising a connecting collar, a sheet metal cap hinged thereto, a sheet metal thimble assembled in the cap and including a flat gasket seat and a tubular portion for supporting the seat from the cap, a gasket, 75 and a detent for holding the cap closed on the collar with the gasket compressed between the same and the gasket seat.

4. An automobile radiator cap comprising a connecting collar, a hollow cap hinged 80 thereto, a thimble member assembled in the cap, a radiator attachment having a stem extending through the top of said cap and said thimble member, securing means in the thimble member securing said attachment to 85 the cap, a dished locking member positioned in said thimble member covering the securing means and having its peripheral edge wedged into said thimble member and a nut 90 threaded on the stem for cooperation with the locking member.

5. An automobile radiator cap comprising a connecting collar, a cap hinged thereto, a thimble member assembled in the cap member, means for retaining said cap in its 95 closed position, a radiator attachment having a stem extending through the top of said cap and said thimble member, means for securing said attachment to said cap, and a dished locking disk covering said securing means and having its peripheral edge wedged against the wall of said thimble member to hold it against removal therefrom.

In testimony whereof I have hereunto subscribed my name.

JOHN F. WHITE.
